PIEZOELECTRIC CRYSTAL FILTER WITH
INDUCTIVE SHUNTNoël Meyer Rust, Chelmsford, England, assignor
to Radio Corporation of America, a corpora-
tion of DelawareApplication April 21, 1937, Serial No. 138,109
In Great Britain April 29, 1936

3 Claims. (Cl. 178—44)

This invention relates to coupling circuit arrangements of the kind including a coupling element constituted by a piezoelectric crystal, and has for its main object to provide improved circuit arrangements of the kind wherein the "carry-through" effect of the crystal may be accurately balanced out or alternatively made to produce a desired definite predetermined effect on the operating characteristics of the circuit arrangements as a whole. The invention is of wide application and may be applied to crystal filters generally, e. g., to crystal filters for use in high selectivity intermediate frequency circuits for superheterodyne receivers and to high selectivity circuits for automatic tuning (automatic frequency control) of radio receivers. As will be seen later, crystal coupling circuit arrangements in accordance with the invention may be accurately designed to give almost any desired form 20 of "in balance" or "out-of-balance" response curve.

The invention provides improved piezoelectric crystal coupling circuit arrangements of the so-called "bridge" type but whereas most known bridge type crystal circuits are essentially capacity bridges (the coupling element which wholly or partly counterbalances the crystal unit in the bridge being a condenser) according to this invention a mutual inductance—i. e., magnetic coupling—is employed to counterbalance the crystal unit. It should be pointed out that the term "counterbalance" as employed in the last sentence is not intended to imply that there shall be exact balance; as will be seen later, the 30 counterbalancing mutual inductance may be made an exact balance, or more than an exact balance, or less than an exact balance, according to the nature of the response curve required, i. e., in dependence upon design requirements. Indeed, one of the major advantages of the invention lies in the facility with which almost any design requirements may be accurately satisfied. Other important advantages of the invention 40 reside in the simplicity of circuits in accordance therewith and their great adaptability to widely different uses.

The invention is illustrated in and explained in connection with the accompanying diagrammatic and graphical drawings in which:

Figure 1 shows a circuit diagram which represents the electric equivalent of a piezoelectric crystal,

Fig. 2 shows a plot of susceptance and conductance as obtained from the circuit of Fig. 1,

Fig. 3 shows a foundation circuit on which my invention is built,

Fig. 4 shows schematically the elementary portions of the circuit in Fig. 3,

Fig. 5 shows a response curve appropriate to Fig. 4,

Fig. 6 is a circuit diagram representative of a preferred embodiment of my invention,

Fig. 7 shows schematically the elements of Fig. 6,

Fig. 8 shows an alternative equivalent to that of Fig. 7,

Fig. 9 shows a second alternative equivalent to that of Fig. 7,

Fig. 10 shows a device for matching the impedance of a piezoelectric crystal,

Figs. 11 and 12 show respectively star and delta circuit equivalents of Fig. 10,

Fig. 13 shows a circuit embodying "resistance cancellation", and

Fig. 14 shows a response curve appropriate to Fig. 13.

For the purposes of the present invention a piezoelectric crystal may be regarded as electrically equivalent (within a limited range of frequencies) to a circuit as shown in Fig. 1 and comprising a large inductance L in series with a small condenser C₁ and with a resistance R, the series sequence of these three elements being shunted by another condenser C₂. To take a practical example a typical 450 k. c. crystal unit was found to be approximately equivalent to a circuit comprising an inductance L of about 53—54 henries, in series with a condenser C₁ of about .0023 micro-micro-farad, in series with a resistance R of about 20,000 ohms (this represents the mechanical damping of the crystal), the shunt condenser C₂ being about .32 micro-micro-farad plus the cross-capacity due to the crystal holder. If, for such a circuit, conductance and susceptance curves be plotted as shown in Fig. 2 with frequency along the abscissa line, the total conductance curve A will, of course, have its peak at the resonant frequency F₀ of the crystal and will approach the abscissa line asymptotically on either side of this frequency; the susceptance curve B due to the series inductance L and capacity C₁ alone will pass through zero at a resonant frequency F₀ and will after reaching a maximum also approach the abscissa line asymptotically on either side of the resonant frequency; the susceptance curve C due to the "carry through" (i. e., the susceptance of the equivalent shunt condenser C₂) will be a line substantially parallel to the abscissa line within the working range of fre-

quencies under consideration; and the total susceptance curve D will, therefore, be displaced relatively to the abscissa line, the said curve passing through zero at two frequencies X, Y, other than the resonant frequency. This has for its effect to render the total admittance curve of the crystal asymmetrical.

Now, if a crystal be used as an interconnecting link between any two parts of an electrical circuit, i. e., as a so-called "crystal gate," its effectiveness in transferring electrical energy from one part to the other at any particular frequency depends on the relationship of the admittance of the equivalent electrical circuit, representing the action of the crystal, to the electrical constants of the two parts of the circuit interconnected thereby. Generally speaking, at any frequency at which the admittance is large, there will be a relatively large transfer of energy and vice versa despite any modifying effect imposed by the impedance-frequency characteristics of the circuit elements interconnected by the crystal. The present invention, by providing a susceptance counterbalancing that due to the carry-through effect, and which causes asymmetry of the admittance curve, enables the said curve to be made substantially completely symmetrical or the asymmetry may be controlled within a wide range to any desired extent.

Thus, consider a circuit as shown in Fig. 3 and comprising two parallel tuned circuits TC_1 , TC_2 , interconnected by means of a crystal PE, the first circuit TC_1 being energized by a high frequency pentode valve V_1 and the second circuit energizing the grid of a subsequent valve V_2 . The equivalent circuit may be represented as shown in Fig. 4 by an A. C. generator G giving an output of μe and connected in series with an impedance ρ across a network consisting of two equal shunt branches each of impedance Z_1 equal to the impedance of a parallel tuned circuit TC_1 or TC_2 (assumed to be identical) and a series branch of impedance Z_c which is the equivalent crystal impedance, e being the voltage applied to the grid of the first valve V_1 , and its magnification factor. If E be the voltage on the grid of the second valve V_2 , i. e., the voltage developed across the second shunt branch Z_1 then,

$$E = \frac{\mu e}{\rho} \times \frac{Z_1^2}{Z_c + 2Z_1}$$

$$\therefore E = g \times \frac{Z_1^2}{Z_c + 2Z_1}$$

where e is, of course, the voltage at the grid of the valve V_1 and g is the mutual conductance of the same valve.

The approximation assumes that ρ the internal impedance of the valve, is much greater than Z_1 .

Such assumption is generally regarded as admissible since ρ in the case of a tetrode or pentode will be of the order of one megohm, whilst Z_1 will usually be of the order of 50,000 ohms or less.

In cases where selectivity is more important than sensitivity the value of Z_1 should be made much less than any value achieved by Z_c over the range of frequencies in question. On this assumption

$$E = \frac{gZ_1^2}{Z_c} = gZ_1^2 Y_c$$

where Y_c is the total admittance of the crystal.

The response curve E in these circumstances

will be as shown in Fig. 5 asymmetrical, having a peak value substantially at the resonance frequency F_0 of the crystal and a valley at Q due to a minimum in the total admittance curve near the point remote from the resonant frequency at which the total susceptance curve crosses the abscissa line. The response curve becomes asymptotic to a line C' substantially parallel to the abscissa line and representing the carry-through effect.

The asymmetrical conditions thus produced may in certain instances be usefully employed but it is, of course, necessary that the effect obtained can be predetermined and controlled. It will be seen that by including a positive or negative susceptance in parallel with the total admittance the shape of the acceptance curve can be controlled. For example, if this additional susceptance be equal but of opposite sign to the carry-through susceptance, the carry-through would be balanced out and the valley would disappear, the resultant curve becoming symmetrical. Alternatively, if a negative susceptance equal to twice the value of the carry-through susceptance be employed, the valley in the response curve will appear at an equal distance on the opposite side of the resonance frequency, the resultant carry-through effect being of the same order of magnitude as before.

If the net susceptance at resonance be small compared with the carry-through susceptance, the resultant carry-through will be small and the valley far removed from the resonance point. As the net susceptance is increased the valley moves nearer to the resonance frequency and the carry-through increases until with a relatively large net susceptance there is a large carry-through accompanied by a very sharp change from peak to valley. The response curve will be symmetrical if the net susceptance at resonance is zero.

The net susceptance at resonance may obviously be increased in a positive sense merely by placing a condenser in parallel with the crystal. The present invention is primarily concerned, however, with means for making this net susceptance zero or negative.

One arrangement, in accordance with the invention, whereby this may be effected in the above described intervalve coupling arrangement of Fig. 3 wherein a crystal PE is utilized to couple the tuned output and input circuits TC_1 , TC_2 of the two valves V_1 , V_2 in question, consists in providing a variable magnetic coupling between the inductances of the two tuned circuits. This arrangement is shown in Fig. 6 where M is the mutual inductance provided by the magnetic coupling.

If L be the value of each of the two inductances and M the value of the mutual inductance in Fig. 6 the equivalent circuit may be represented as shown in Fig. 7 by a Y or star inductance network the upper limbs of which are of value $L-M$ and the central lower limb of which is of value M . This Y or star network may be replaced as shown in Fig. 8 by a Δ or mesh network having inductance values

$$\frac{L^2}{M-M}$$

$L+M$ and $L-M$ respectively. Thus, the two coupled circuite TC_1 , TC_2 may be replaced as shown in Fig. 9 by two tuned circuits each having an inductance of value $L+M$ coupled by the

crystal and an inductance in parallel therewith of value

$$\frac{L^2}{M} - M$$

5 This holds good whether M be positive or negative and if M be small compared with L .

$$\frac{L^2}{M} - M$$

10 is large and will be negative when M is negative. Thus, if the magnetic coupling be such that the value and sign of M can be varied, it is easily and conveniently possible to vary the response characteristics of the circuit to meet widely varying requirements. Very small values of M will be required and usually M can be neglected in comparison with

$$\frac{L^2}{M}$$

20 so that

$$\frac{L^2}{M} - M = \frac{L^2}{M}$$

25 Thus, the impedance will be proportional to

$$\frac{L^2}{M}$$

and hence the susceptance to

$$\frac{\omega M}{L^2}$$

30 Since the range of frequencies over which the crystal is effective is, of course, relatively very small, the parallel susceptance provided by the mutual inductance is substantially proportional to M . In this way it is a simple matter to balance out to a desired degree the carry-through susceptance.

35 In order to match the crystal impedance to that of the tuned circuits, the terminals of the crystal PE may be tapped down on the inductances of the tuned circuits TC_1 , TC_2 . A circuit in which this expedient had been adopted and 40 by means of which experimental data have been obtained, is shown in Fig. 10 and comprises a high frequency pentode V_1 having in its anode circuit a parallel tuned circuit TC_1 comprising a main tapped inductance in series with a small coupling inductance, said two inductances having a variable condenser connected in parallel therewith. An exactly similar parallel tuned circuit TC_2 is connected between the grid and cathode of a valve voltmeter (not shown). The 45 main tapped inductances are separately screened and a variable magnetic coupling M is provided between the coupling inductances, said inductances being located in common screening means and having electrostatic shielding means therefore, to permit of magnetic coupling only. The crystal PE is connected between corresponding taps on the two tapped main inductances. The screening is represented by chain lines.

50 By applying varying frequencies to the grid of the pentode valve V_1 various response curves were plotted by taking corresponding readings of output with different values of inductive coupling M and it was found possible to obtain not only a substantially perfectly symmetrical curve but 55 almost any degree of asymmetry desired, depending on the value and sense of the magnetic coupling.

55 The invention is, of course, not limited to this form of circuit arrangement and the circuit elements coupled by the crystal may be of

any desired kind, for example, chokes or even in some instances ohmic resistances.

The invention is applicable to all forms of simple crystal filter arrangements where it is desired to obtain a sharp symmetrical response curve or an asymmetrical response curve in which rate of change in decibels per cycle is greater on one side than on the other, and also to cases where it is desired to use both a peak and valley one for acceptance and the other for rejection 10 of desired frequencies.

In the description so far given only what may be termed "susceptance cancellation" methods have been described, the mutual inductance being employed to compensate or to under-compensate or over-compensate (to a desired degree) effects of stray capacities. Resistance effects have been neglected so far. The effect of resistance in the coils of the tuned circuits of a network such as that shown in Fig. 6 (and whose equivalent circuit, neglecting resistance is shown in "star" form in Fig. 7) will be seen from Fig. 11, which is like Fig. 7 except for the added resistance R representing an inserted resistance which is "mutual" to both circuits and two resistances R' (each given by

$$R' = \frac{\omega L}{Q}$$

representing the high frequency resistances of the two coils. The equivalent "delta" circuit is shown by Fig. 12 in which Z_3 is given by

$$Z_3 = \frac{2\omega L^2}{QM} - \frac{RL^2}{M^2} + j\left(\frac{\omega L^2}{M} + \frac{2RL^2}{QM^2}\right)$$

35 where Q is the "Q" value of the coils.

The reactance term

$$\frac{j\omega L^2}{M}$$

40 is dependent in sign and value upon the sign and magnitude (respectively) of the mutual inductance M . The other reactance term is always positive and usually negligible as compared to

$$\frac{\omega L^2}{M}$$

45 The resistance term consists of two terms—term

$$\frac{2\omega L^2}{QM}$$

50 which is dependent as to sign and magnitude on M and as to magnitude alone upon Q . The second term is always negative and, being dependent upon R , can be controlled by varying R . The second resistance term may, in general, be made to predominate over the first term and controllable "resistance cancellation" may, therefore, be obtained.

55 Fig. 13 shows a circuit embodying controllable "resistance cancellation" means in the form of a variable resistance RX . As will be seen, except for the provision of RX and the fact that the anode circuit of V_1 is shown inductively coupled to circuit TC_1 , Fig. 13 is like Fig. 6. To 60 take a practical example for a 450 k. c. cycle, M may be variable from + to -70 micro-henries and RX may be variable from 0 to 120 ohms, the main (uncoupled) coils in the tuned circuits TC_1 , TC_2 being of 700 micro-henries each. Varying 65 the resistance RX practically affects only the "valley" depth in the response curve, having little or no effect on the "peaks." The insertion of the resistance to effect "resistance cancellation" produces a deep valley in the response 70 75

curve. This is shown in Fig. 14 in which the full line curve shows the result obtained with resistance cancellation and the broken line curve the way in which the valley practically disappears without resistance cancellation.

I claim:

1. An electric wave filter system connected between the output circuit of an electron discharge tube and a utilization device, said system comprising a tuned circuit connected to said output circuit and a second tuned circuit connected to said utilization device, each of said tuned circuits having a variable capacitor, an isolated inductance portion and a magnetic coupling portion, the two magnetic coupling portions constituting the primary and secondary, respectively of a transformer, a series of taps disposed intermediate the terminals of said isolated inductance portions, a piezoelectric device having its two electrodes selectively connected in circuit between one of the taps of one isolated inductance and one of the taps of the other isolated inductance, and means for varying the reactance between the primary and secondary of said transformer.
2. An electric wave filter having an asymmetrical frequency response characteristic and having a piezoelectric crystal for determining said characteristic, parallel tuned circuits each connected to its respective electrode of said piezoelectric crystal, one parallel tuned circuit having a minor portion of its inductance coupled to a similar minor portion of the inductance in the other parallel tuned circuit, and means for varying the degree of magnetic coupling between the

two said parallel tuned circuits, thereby to obtain a rejection frequency which in one case is considerably lower and in another case is considerably higher than the frequency of maximum response.

3. A filter system inductively coupled to the output circuit of one electron discharge tube and connected to the input circuit of a second electron discharge tube, comprising two tuned circuits each constituted by a capacitor in shunt with a plurality of separate inductance portions, one of the inductance portions in one tuned circuit being magnetically coupled to a corresponding inductance portion in the second tuned circuit, the remaining inductance portions being substantially reactively isolated from one another, a source of biasing potential in a circuit including the cathode of the second tube, the inductance portions of the second tuned circuit and the control grid of said second tube, a piezoelectric device connected across corresponding points of said tuned circuits, and means for varying the response characteristic of said filter system as a whole in such manner that an asymmetrical curve of rejection frequency is obtained which curve extends from a point considerably lower than the main resonant frequency through a condition in which the rejection frequency is brought close to the resonant frequency and extending on the other side thereof through a point where the rejection frequency is considerably higher than said resonant frequency.

NOËL MEYER RUST.
